Primary Examiner — Garth Rademaker*Assistant Examiner* — Llorellys Martinez-Rivera(74) *Attorney, Agent, or Firm* — Winthrop & Weinstine, P.A.(57) **CLAIM**

The ornamental design for an electronic lighting device, as shown and described.

DESCRIPTION

FIG. 1 is a front perspective view of an electronic lighting device of the present disclosure;

FIG. 2 is a rear perspective view of the electronic lighting device of FIG. 1;

FIG. 3 is a right side view of the electronic lighting device of FIG. 1;

FIG. 4 is a front view of the electronic lighting device of FIG. 1;

FIG. 5 is a left side view of the electronic lighting device of FIG. 1;

FIG. 6 is a back view of the electronic lighting device of FIG. 1;

FIG. 7 is a top view of the electronic lighting device of FIG. 1; and,

FIG. 8 is a bottom view of the electronic lighting device of FIG. 1.

The broken lines shown in FIGS. 1, 3-5, 7, and 8 illustrate portions of the electronic lighting device that form no part of the presently claimed design.
